BALL TOSSING AND CATCHING GAME DEVICE

Filed April 13, 1944

Inventor:

James Jernigan Sanders

UNITED STATES PATENT OFFICE

138,360

DESIGN FOR A BALL TOSSING AND CATCHING GAME DEVICE

James Jernigan Sanders, Nashville, Tenn.

Application April 13, 1944, Serial No. 113,234

Term of patent 14 years

(Cl. D34—15)

To all whom it may concern:

Be it known that I, James Jernigan Sanders, a citizen of the United States, residing at Nashville, in the county of Davidson and State of Tennessee, have invented a new, original, and ornamental Design for a Ball Tossing and Catching Game Device, of which the following is a specification, reference being had to the accompanying drawing, forming part thereof.

The figure is a perspective view of a ball tossing and catch game device, showing my new design.

I claim:

The ornamental design for a ball tossing and catching game device, as shown.

JAMES JERNIGAN SANDERS.
